MARTIN MICKELSON, INVENTOR.

BY

Richard B. Owen,
ATTORNEY.

UNITED STATES PATENT OFFICE.

MARTIN MICKELSON, OF MUSKEGON HEIGHTS, MICHIGAN.

ELEVATOR DEVICE.

1,415,603.

Specification of Letters Patent.

Patented May 9, 1922.

Application filed July 28, 1920. Serial No. 399,518.

To all whom it may concern:

Be it known that I, MARTIN MICKELSON, a citizen of the United States, residing at Muskegon Heights, in the county of Muskegon and State of Michigan, have invented 5 certain new and useful Improvements in Elevator Devices, of which the following is a specification.

The object of the present invention is 10 to provide new and novel means in the nature of a hoist or elevator lift whereby the raising and lowering of the car or cage may be accomplished in a smooth and efficient manner.

15 An additional object is to provide an elevator lift or hoist mechanism including means for hoisting and lowering purposes; the said means being in the nature of a screw drive so that the position of the car 20 is continuously varied as long as the drive mechanism is in operation.

With the above and other objects in view, the invention may be said to reside generally in the details of construction, combination and arrangement of parts, as will be hereinafter more fully pointed out, reference being had to the accompanying drawings, wherein—

Figure 1 is a side elevation illustrating 30 the application of the invention.

Figure 2 is a horizontal cross section disclosing the manner in which the car is mounted in the elevator shaft or frame, and

Figure 3 is an enlarged detailed view, in 35 section, of the track.

In the drawings, 1 indicates an elevator shaft or the frame within which the elevator car is mounted for movement and this frame is provided on one side with a door-way 2. 40 When installed in a building, this shaft would, of course, extend from the basement to the roof thereof usually and a door way would be provided for each floor so that access to the lift or elevator could be had 45 on any floor of the building. The frame is provided on two sides with a guide way 3, preferably of a channeled construction, for engagement with guides 4 arranged in suitable numbers and at appropriate places on 50 the elevator car 5. The car 5 may be of any suitable construction and is provided with a door way 6 to register with the door ways 2 of the frame as the car moves vertically within the shaft. At its top and bottom, 55 the car is provided with an opening 7 forming the outlet of a well 8 running

longitudinally of the elevator car and partitioned off from the remainder of the car, as illustrated. This well provides for the passage, through the center of the car, of a supporting column or drive shaft 9 upon which the car is mounted for movement. This column 9 is provided with reduced ends 10 provided each with enlarged heads 11 which fit into the sockets 12 of the bearings 65 or brackets 13 located at the top and bottom of the elevator shaft as shown in Figure 1. Suitable friction bearings 14 are provided in each socket, beneath each head 12 to enable the column to be readily rotated 70 about its axis for raising or lowering the car.

Rigid with the lower end 10 of the column is a large gear 15 and meshing with this gear is a pinion or worm 16 of a motor drive 17. It is intended that the motor 75 drive be controlled from the elevator car and accordingly any suitable controlling mechanism may be located in the car and electrically connected to the drive for regulating the movement of the car. It is 80 obvious that when the motor is started, the worm 16 through its engagement with the gear 15 will cause the latter to turn and revolve the column 9 on the bearings 14. To enable the revolving column 9 to impart movement to the car 3, the former is provided with an outstanding continuous rib or flange 18 threaded in a spiral curve from one end of the column to the other as 85 shown in the drawings. This flange carries 90 a rim or ridge 19 spaced outwardly from the body of the column and providing a spiral track which changes its position after the manner of the threads of a screw during the rotation of the column. Designed for 95 engagement with the spiral track are a pair of track wheels 20. These wheels revolve on axles 21 carried by brackets 22, preferably affixed to opposite side walls of the well 8 and adjacent the bottom of the car, being 100 relatively offset to engage the track at disaligned points for keeping the car in a vertical position. These wheels or track rollers 20 are supported, it is to be noted, outwardly from the sides of the well and are 105 flanged to keep the car from coming in contact with the revolving track.

When the device is set up, the car 3 is mounted upon the rotatable column 9 so as to be slidable within the elevator frame or 110 shaft 1, the guide 3 of the car sliding within the guide ways 4 and steadyng the move-

ment of the car as it moves up and down along the column 9. When it is desired to raise or lower the car, the operator starts the motor 17 for rotating the gear 15 and 5 the column 9. As the spiral track 18 revolves with the column after the manner of a screw thread, it exerts a lifting force against the rollers 20 which causes the car to move upwardly along the column at a 10 rate of speed proportionate to the revolutions of the supporting member 9. In lowering the car, the screw column is reversed and the weight of the car enables it to drop easily as the track recedes. A push button 15 23 or other suitable signalling means may be located on each floor of the building in which the elevator is installed and is electrically connected to the motor 17.

From the foregoing, it may be seen that 20 the invention contemplates the provision of a novel form of elevator lift or hoist wherein the car is lifted by the screw action of a rotating supporting column which passes through a well or partitioned portion of the 25 car and which is mounted to turn easily, upon suitable bearings, under the control of the operator. It is of course to be understood that minor changes in the character of invention and the details of construction, etc., may be resorted to as long as they 30

fall within the purview of the invention as defined in the appended claim.

Having thus fully described my invention, what I claim as new and desire to secure by Letters Patent is:—

35 In a device of the character described, the combination with two vertically held guide rails, of an upper and lower bearing located between the said rails, a vertically held screw column the ends of which are reduced and 40 provided with an enlarged bearing head arranged for cooperation with said bearings, a worm held to the lower end of said column, a car having a suitable bottom, said car provided with a vertically extending well 45 passing through the same and enclosing said column, a spiral on the screw column having an upstanding rim, brackets secured to the said car bottom, a grooved roller carried by the said brackets and arranged to ride 50 on said upstanding rim, and a guide carried by the said car for engagement with said guide rails, all as and for the purpose set forth.

55 In testimony whereof I affix my signature in presence of two witnesses.

MARTIN MICKELSON.
